GEORGE N. BLANCHARD, OF SAN FRANCISCO, CALIFORNIA, ASSIGNOR OF ONE-HALF
TO WILLIAM HENRY BUSCH, JR., OF SAN FRANCISCO, CALIFORNIA.

THERMO-ELECTRIC REGULATING SYSTEM.

1,141,307.

Specification of Letters Patent.

Patented June 1, 1915.

Application filed December 2, 1912. Serial No. 734,546.

To all whom it may concern:

Be it known that I, GEORGE N. BLANCHARD, a citizen of the United States, residing in the city and county of San Francisco and 5 State of California, have invented certain new and useful Improvements in Thermo-Electric Regulating Systems, of which the following is a specification.

The hereinafter described invention relates to an improved thermo-electric apparatus for automatically regulating the temperature of an inclosure, but is more particularly designed for use in cold storage houses, where it is desired to maintain constant 10 the temperature of the interior thereof at all times, so that perishable articles stored therein, such as meat, poultry and eggs, will at all times be preserved in a temperature varying only a fraction of a 15 degree.

The invention has for its principal object to provide an apparatus of the above character which is very sensitive to the changes in temperature, that is, capable of being adjusted 20 to operate within a fraction of a degree of temperature, or a wide range of temperature, and which is electrically connected to the controlling means of a supply of cooling fluid, the electrical connections being 25 made or broken by the rise or fall of pressure in the apparatus, which is controlled by the rise or fall of the temperature within the room.

The invention consists in a closed system 30 of suitable hollow tubing containing a fluid sensitive to the changes of temperature, and hereinafter termed a thermo-system, a mercury tube provided with a capillary bore and formed at its lower end with an inner 35 and outer bulb communicating at their lower ends, said bulbs partly filled with mercury, a communication between said hollow tubing and the upper portion of said outer bulb, pressure actuated means connected to said 40 system of tubing and operated by the expansion of the fluid therein, an electrically operated valve controlling a supply of cooling fluid, electrical connections between said 45 electrically operated valve and said pressure actuated means, said pressure actuated means making or breaking electrical contacts to operate said valve to open or close according to the expansion or contraction of the fluid in said thermo-system.

50 With the above mentioned and other objects

in view the invention consists in the novel construction and combination of parts hereinafter fully described; illustrated in the accompanying sheets of drawings, and pointed out in the claims hereto appended; it being understood that various changes in the form, proportion, size and minor details of construction, within the scope of the claims hereto appended, may be resorted to without departing from the spirit or sacrificing any of the advantages of the invention.

To more fully comprehend the invention, reference should be had to the accompanying sheets of drawings, wherein—

Figure 1 is a view in elevation of my improved apparatus, disclosing the electrically operated valve controlled brine supply pipe, the thermo-system, the mercury tube connected therewith, and the pressure operated device connected to said thermo-system for controlling the operation of said electrically operated valve controlling said brine supply pipe. Fig. 2 is a view in detail of the electric circuit for controlling the operation of the electrically operated valve and the pressure actuated arm for controlling the circuit.

Referring more particularly to the drawings, the reference numeral 1 designates connected coils of suitable hollow tubing, the coils being of any convenient shape and are adapted to contain to their full capacity a suitable fluid which is sensitive to the changes of temperature, preferably alcohol, the fluid when subjected to warm temperature expanding and creating greater pressure in the coils than when it is subjected to a cold temperature and contracts in the coils.

Connected to the interior of the coils 1 through a suitable coupling 2 is a suitable pressure actuated controller, mounted in the usual casing 3 and formed with a hollow curved spring arm 4 of the Bourdon type, closed at one end and connected to and communicating with the coupling 2 at its opposite end.

Connected to but insulated from the closed end of the hollow, curved spring arm 4 is a movable contact finger 5, adapted to be thrown in or out of contact with the adjustable stationary contact points 6 and 7, positioned one on either side of the finger 5 and insulated from the casing 3, in any suitable manner.

The temperature of the inclosure in which my regulator is positioned is controlled by a suitable cooling fluid, preferably a brine solution, and the same is adapted to circulate 5 through a system of piping 8 which extends around the inclosure in any suitable manner.

The circulation of the brine solution is controlled by suitable valves associated with 10 openings in a valve casing 11, and from said valves extend a common valve stem 12, operated by suitable magnet coils 15 and 16, mounted in a casing 17, supported above 15 the valve casing by the rods 18. The magnet coils are connected to each other by a lead 19 and are connected at their ends by the leads 20 and 21 with a suitable source 20 of electric energy. A lead 22 extends from the finger 5 to the lead 19, contact 6 is connected by a lead 23 to the lead 21, and contact 7 is connected by a lead 24 with the lead 20, which construction is disclosed in Fig. 2 of the drawings.

A mercury tube 25, preferably formed of glass, provided with a capillary bore 26 extending through the center thereof and formed with an enlarged bore 27 at its lower end, which communicates at its lower end, as at 28, with an enlarged chamber 29 surrounding the bore 27, is mounted within a 30 casing 30, supported in any suitable manner by the tubing 1, and the enlarged chamber 29 is connected at its upper end with the thermo-coils 1 by a small tube 31, and is filled for a portion of its capacity with a 35 fluid 32', preferably mercury, as its high specific gravity produces greater changes of pressure, for any given vertical movement of the column than would be the case with a lighter fluid.

40 From the above description it will be observed that as the temperature in the room in which the device is mounted rises, the alcohol in the thermo system 1 will be heated and will expand. As the alcohol expands, a 45 certain portion of it is forced through the tube 31 into the upper end of the enlarged chamber 29, the expanding alcohol forcing the mercury at the lower end of the tube 28 upwardly in the center of the bore 27 and 50 into the capillary bore 26 of the tube 25 and the higher the mercury is forced in the bore 26 by the expansion of the alcohol in the thermo-system, the greater the increase of pressure in the system. As the pressure increases in the system 1 it also increases in 55 the hollow spring arm 4, and when it reaches a point sufficient to overcome the tension of the spring arm 4, the finger 5 of which is normally out of contact with the stationary 60 contacts 6 and 7, the arm will be raised, the finger 5 making contact with 6, as shown in Fig. 3.

The magnet coil 15 now being short circuited and the coil 16 being fully energized, 65 the valve stem 12 will be drawn downwardly

in the casing 17 and the valves 9 will be unseated from their openings 10 allowing a cooling or brine solution to circulate through the cooling system 8.

The electrical connections from the source 70 of electric energy to the magnet coils 15 and 16 is such that sufficient electricity is at all times circulating through the coil when the finger 5 is out of contact with the contacts 6 and 7, to maintain the valve stem in either 75 position until it is moved by the short circuiting of one of the coils.

As the temperature of the inclosure is reduced by the circulation of the brine solution through the cooling system, the falling 80 temperature will cause the alcohol in the thermo-system 1 to contract, the mercury also receding in the capillary bore 26 on the contracting of the alcohol in the system 1, and as the level of the mercury drops in 85 the capillary bore 26 the pressure is reduced in the system. When the pressure in the system has reduced sufficiently, the tension 90 of the spring 4 will overcome the pressure that is tending to expand it and will contract, and the finger 5 carried by the end thereof will break contact with the contact 6, fully energizing the coil 15 and will make contact with the contact 7, short circuiting the coil 16; by this action the valve 95 stem 12 will be drawn upwardly in the casing 17 and the valves 9 will be seated in the openings 10, cutting off the circulation of the brine solution through the cooling system 8.

100 A hollow pressure regulating tube 32 communicates with the interior of the thermo system 1 and in said tube is mounted a plunger head 33 carried on the lower end of an adjustable screw-threaded rod 34, the 105 threads of which intermesh with suitable threads on the interior of the tube 32, and by adjusting the plunger in the tube the pressure in the system will be regulated, forcing the mercury either high or low in 110 the bore 26 so that it will require a considerable or not much expansion of the fluid in the system to force the mercury to such height in the bore 26 that it will create sufficient pressure to operate the arm 4.

115 It will be observed that by the employment of the pressure regulating tube 32 the system may be readily adjusted to operate upon a slight variation of a degree or at any desired temperature.

120 Having thus fully described my invention what is claimed as new and is desired to be protected by Letters Patent is—

1. In a regulating system of the class described, the combination with a Bourdon tube, electric circuits controlled by the movement thereof a thermo chamber, a connection between said chamber and said Bourdon tube, a body of confined liquid, and a connection between the interior of said thermo 125 130

chamber and said body of confined liquid, said liquid being operated by variations of pressure in the thermo chamber for opposing the pressures therein to regulate the operation of said Bourdon tube to make or break the electric circuit controlled thereby.

2. In a regulating system of the class described, the combination with a Bourdon tube, electric circuits controlled by the movement thereof a thermo chamber, a connection between said chamber and said Bourdon tube, a body of confined mercury, and a connection between the interior of said thermo chamber and said body of confined mercury,

15 said mercury being operated by variations of pressure in the thermo chamber for opposing the pressures therein to regulate the operation of said Bourdon tube to make or break the electric circuit controlled thereby.

20 3. In a regulating system of the class described, the combination with a Bourdon tube, electric circuits controlled by the movement thereof a thermo chamber, a connection between said chamber and said Bourdon tube, means in said chamber for regulating the pressure therein independently of the rise or fall of temperature around said chamber, a body of confined liquid, and a connection between said thermo chamber

25 30 and said body of confined liquid, said liquid being operated by variations of pressure in the thermo chamber for opposing the pressures therein to regulate the operation of said Bourdon tube to make or break the electric circuit controlled thereby.

35 4. In a regulating system of the class described, the combination of a Bourdon tube, electric circuits controlled thereby, a thermo coil, a connection between said coil and said

40 tube, vertically disposed a tube provided

with a capillary bore terminating at its lower end in an enlarged bore open at its lower end and surrounded by an enlarged chamber adapted to contain a body of mercury, and a connection between the interior 45 of said thermo coil and said last mentioned chamber, whereby the height of the body of mercury in said capillary bore is regulated by variations of pressure in the thermo coil, and said mercury as it rises and falls in said 50 capillary bore opposing the pressures in said thermo coil to regulate the operation of said Bourdon tube to make or break the electric circuits controlled thereby.

5. In a regulating system of the class described, the combination of a Bourdon tube, electric circuits controlled thereby, a thermo coil, a connection between said coil and said tube, means in said coil for regulating the pressure therein independently of the rise or 55 fall of temperature around said coil, a vertically extended tube provided with a capillary bore terminating at its lower end in an enlarged bore open at its lower end, and surrounded by an enlarged chamber adapted 60 to contain a body of mercury, and a connection between the interior of said thermo coil and said last mentioned chamber, whereby the height of the body of mercury in said 65 capillary bore is regulated by variations of 70 pressure in the thermo coil to regulate the operation of said Bourdon tube to make or break the electric circuit controlled thereby.

In testimony whereof I have signed my name to this specification in the presence of 75 two subscribing witnesses.

GEORGE N. BLANCHARD.
